UNITED STATES PATENT OFFICE.

NELS EST, OF MONTESANO, WASHINGTON.

DEEP-SEA RAFT.

Application filed October 31, 1922. Serial No. 593,058.

To all whom it may concern:

Be it known that I, NELS EST, a citizen of the United States of America, and resident of the city of Montesano, in Grays Harbor County, State of Washington, have invented certain new and useful Improvements in Deep-Sea Rafts, of which the following is a specification.

My invention relates to rafts of the kind used in transporting large quantities of timber by water.

The principal object of my invention is to provide means whereby logs may be connected in rafts and towed at sea in such a way that the danger of the raft breaking up in heavy weather is greatly minimized.

A further object is the provision of a raft which requires no specially built wharf or cradle, and which may be built in water only deep enough to float the logs.

A further object is the provision of a raft which is simple and cheaply constructed, and the metal securing parts of which may be used again.

A further object is the provision of a raft which in case of necessity may pass through a narrow channel.

My invention comprises the novel arrangement of parts which is shown in the accompanying drawing, which will be described in the present specification and particularly defined by the claims terminating the same.

In the accompanying drawing my invention is shown in its present preferred arrangement.

The drawing shows a plan view of a raft constructed according to my invention.

Along the Pacific coast there are many places where large trees grow near the water's edge and which may be profitably used except for the difficulty of transporting them to the mills. By means of my raft these trees can be dragged a short distance to the water and the whole tree, or as much thereof as can be used for lumber, can be floated. If a raft can be constructed of these logs without special apparatus, which is expensive and difficult to transport, or

special wharves or cradles, which are difficult to build in such remote territories as the timber is to be found, the timber can be profitably transported to the mills. However, there is often danger of a log raft being broken by heavy weather, particularly if all parts are rigid. It has been my object, therefore, to make my raft as flexi-

ble as possible while yet securing the component logs securely together.

The various logs 1 which form the individual parts of my raft are arranged in sections, each section being placed immediately behind the section next preceding it. The logs in each section are flexibly secured together, and to this end I have shown each log as transversely bored at its forward end, 65 as indicated at 2, and through this bore I pass a cable 3. The ends of this cable may be united to form a towing bridle, clamps 5 being employed for this purpose.

The various sections must be flexibly secured together and yet the logs must be confined so that they will not spread, particularly if stopped in open water. I have therefore, shown one or more of the outermost logs 1' in each section as being transversely bored at its rear end and as indicated at 4. If desired the cable forming the towing bridle 3 of a rear section may be passed directly through the bores 4 in the outer logs of the next section forward. Preferably, but not necessarily, these outer logs 1' are somewhat longer than the inner logs 1 and thus one bight of the cable 3 is left free of the inner logs. These inner logs 1 are then free to move up and down, but 85 are confined against spreading by the spaced and connected outer logs 1'. It will be understood that a tow line 6 will be connected to the forward bridle 3 instead of connecting this bridle to any forward section. 90

The last section may be constructed as described above, except that it is preferable to pass one bight of a cable 7 over all of the logs in the section, thence through the bores 4 at the rear ends of the outermost 95 logs, and thence beneath all of the logs in this section. In this manner all of the rear ends are connected together, however flexibly, but are prevented from being displaced relative to each other by following seas or otherwise.

Such a raft may be constructed in water only deep enough to float the individual logs. The rear ends of all logs in each section, except perhaps the outside logs 1', 105 are free to move relative to each other except as they are confined to a vertical motion by the outer logs 1'. The various sections are also flexible with respect to each other. In passing through a narrow channel, if necessary the outside logs may be crowded in at their rear ends to lie upon 110

each other to permit passage through such channel.

I have shown the majority of the logs in each section as having their smaller ends forward and their butt ends to the rear. This should not be universally the case, however, as some of the logs should have their butt ends forward to balance the section somewhat. At the same time, it is desirable that the forward end of each section should be somewhat less in breadth than the rear end of the section next in advance thereof. Thus if the forward section can pass through a channel the forward end of the following section will follow the first section and will not strike upon any obstructions to tie up the raft.

What I claim as my invention is:

1. A deep-sea raft comprising a plurality of sections of floating logs, the logs in each section extending longitudinally, all of the logs in a section being flexibly connected at their forward ends, and the outermost logs only being flexibly connected at their rear ends to the following section.

2. A deep-sea raft comprising a plurality

of sections of longitudinally-extending floating logs, a cable flexibly connecting all of the logs in a section at their forward ends, and thence extending forward to connect with the rear ends of the outer logs only of the section next in advance thereof.

3. A deep-sea raft comprising a plurality of sections of longitudinally-extending floating logs, the forward ends of all of the logs of a section and the rear ends of the outer logs of a section being bored, and a single cable passing through the bores at the forward ends of all logs in a given section, and passing also through the bores in the rear ends of the outer logs in the next section in advance thereof, and means connecting together the ends of said cable.

4. A deep-sea raft as in claim 3, the outermost logs of a forward section being longer than the intermediate logs thereof, whereby the cable is clear of the intermediate logs.

Signed at Seattle, King County, Washington, this 23rd day of October, 1922.

NELS EST.
